UNITED STATES PATENT OFFICE.

RANSOM W. DAVENPORT, OF DETROIT, MICHIGAN, ASSIGNOR TO DETROIT STOVE WORKS, OF DETROIT, MICHIGAN, A CORPORATION OF MICHIGAN.

ILLUMINATED SWITCH AND INDICATOR.

1,213,845.

Specification of Letters Patent. Patented Jan. 30, 1917.

Application filed September 23, 1915. Serial No. 52,301.

To all whom it may concern:

Be it known that I, RANSOM W. DAVENPORT, a citizen of the United States of America, residing at Detroit, in the county 5 of Wayne and State of Michigan, have invented certain new and useful Improvements in Illuminated Switches and Indicators, of which the following is a specification, reference being had therein to the 10 accompanying drawings.

The invention relates to electrical heating apparatus; more particularly electric cooking ranges, and it is the object of the invention to provide an indicating controlling switch which is automatically illuminated when the apparatus is in service.

It is usual in the construction of electric ranges to place the controlling switches in the front of the range beneath the projecting top plate, and it is also common to use switches having dial indicators showing the varying degrees of heat by such markings as "high", "low", "medium" and "off". As the indications on the dial are more or less 25 shadowed by the location of the switch they are often difficult to read. I have therefore provided means for illuminating the dial whenever the circuit controlled by the switch is closed, and have further utilized 30 this illuminating means as an indicator that the device is in operation, thus reducing waste of current through the operator's forgetfulness, by constantly reminding him that the current is on.

35 In the drawings; Figure 1 is a view showing in section a portion of an electric range to which my improvement is applied. Fig. 2 is a detail view of the temperature indicating means associated with the switch.

40 A is the top-plate of the range having the forwardly-projecting flange portion B.

C is a casing located beneath said top-plate in rear of said projecting flange, and D and E are respectively a controlling 45 switch and a fuse box located in said casing. The switch D is preferably of a construction provided with an indicator dial, which as shown is formed on a bevel face F. The body of the switch is preferably made within 50 the casing C, but the beveled dial portion is exposed at the front in a recess or niche G in the front wall of the case.

To facilitate the reading of the dial, I have arranged within the case C above the 55 switch an electric lamp H. This is so posi-

tioned that the light will be directed downward upon a portion of the bevel face of the dial, the portion illuminated being that on which the reading is taken. A bull's-eye I is also preferably arranged in the front 60 wall of the case opposite the lamp H, so that a portion of the light will be directed therethrough. When properly constructed this bull's-eye will always glow when the lamp is in operation and will be observable 65 from all directions, so as to indicate the operation of the range.

The lamp H can be placed in circuit either in series or in shunt, but preferably as shown, it is placed in a circuit J which is 70 in shunt with a heater K controlled by the switch. In operation, whenever the switch D is turned on, the lamp H will be illuminated and a portion of the light is directed upon the dial F. The bevel face of this dial is favorable to observation of the indications thereon by a person in front of the range, and avoids the necessity of stooping to the level of the switch. At the same time the bull's-eye will retract the light to disperse it in all directions and consequently 75 an observer from any point in the room can detect whether or not the stove is in operation.

What I claim as my invention is:—

1. In an electric cooking range, the combination with an electric circuit of an electric switch for controlling said circuit, including a heating unit, a casing for inclosing 80 said switch, an indicating dial associated with the switch within the casing, the casing being apertured to permit reading of said dial, and a lamp within said casing and controlled by said switch for illuminating said dial upon the closing of said 85 circuit.

2. The combination with an electric cooking range, of a controlling switch therefor, an indicator on said switch having an inclined face, a housing in which 90 said switch is placed apertured for the observation of said indicator, a lamp within said housing for illuminating said indicator when the circuit is closed, and a bull's-eye 95 also illuminated by said lamp and observable from all directions.

3. In an electric cooking range, the combination with an electric circuit, including a heating unit, of a controlling switch 100 therefor, an indicator on said switch having 105

ing an inclined face, a casing for inclosing said switch, apertured to permit reading of the indications, and a lamp within said casing and controlled by said switch for illuminating said indicator upon the closing of the circuit.

4. The combination with an electric circuit, of an indicating switch for controlling the same, a casing for inclosing said switch 10 apertured to permit the reading of the indications, a bull's-eye in the casing, and a lamp within the casing for independently illuminating said bull's-eye and the indicating switch.
5. The combination with an electric cir- 15

cuit, of a controlling switch therefor, an indicator on said switch, a casing for inclosing said switch having an aperture opposite said indicator and having a second aperture, and a lamp within the casing positioned to throw light directly through said second aperture and indirectly through the aperture adjacent the indicator by reflection from the indicating surface. 20

In testimony whereof I affix my signature in presence of two witnesses. 25

RANSOM W. DAVENPORT.
